FUEL BURNER

Ralph M. Hardgrove, Bethlehem, Pa., assignor,
by mesne assignments, to The Babcock &
Wilcox Company, Newark, N. J., a corpora-
tion of New Jersey

Application August 20, 1929, Serial No. 387,214

24 Claims. (Cl. 122—235)

This invention relates to a burner that is especially useful for burning pulverized coal. The invention will be understood from the description in connection with the accompanying drawings, 5 in which Fig. 1 is a vertical section through an illustrative embodiment of the invention; Fig. 2 is a partial rear view of the structure shown in Fig. 1; Fig. 3 is a plan view, partly in section, showing the burner; Fig. 4 is a plan view of one of the 10 details; Fig. 5 is a section along the line 5—5 of Fig. 4; Fig. 6 is a section along the line 6—6 of Fig. 5; Fig. 7 is a perspective view partly in section of the fuel burner with the deflector blocks and some of the wall tubes omitted; and Fig. 8 15 is a horizontal section showing the relative arrangement of the deflector blocks and tubes.

In the drawings, reference character 1 indicates a furnace having vertically disposed spaced tubes 2 in its wall. The tubes 2 have their ends connected to a header 3 outside of the furnace. 20 The tubes may have water or other cooling fluid circulated through them in the well-known way. The tubes are lined with blocks 4 to provide a continuous wall. Some of the blocks 4 are omitted to provide a location for the fuel burner. The fuel burner has a long narrow mouth or exit opening which extends across a plurality of the tubes, so that fuel from the burner passes into the furnace through a number of spaces between 25 the tubes 2.

The burner 5 is connected to a flaring connection 6, which is in turn connected with a fuel delivery pipe 6^a. The burner 5 is disposed at an angle to the fuel delivery pipe 6^a, and the flaring 30 connection joining the burner and the fuel delivery pipe is provided with a sloping wall 7 against which the mixture of air and powdered fuel from any convenient source impinges so that the mixture will spread out laterally substantially 35 uniformly in the horizontally extending portion of the burner 5. The sloping wall 7 stands at an angle to the axes of the fuel delivery pipe and the burner, as will be realized upon examination of Figure 1. An outlet 8 is connected to the exit end 40 of the burner 5 and may be attached to the tubes 2 in any convenient manner. The outlet 8 extends across a number of the tubes and is provided with outwardly flaring upper and lower walls 9. Each of the tubes 2 has its outer side contacting with 45 the concave side of a crescent shaped shield 8^a, as shown in Fig. 3, the upper and lower edges of which fit into recesses formed in the upper and lower walls 9 of the burner outlet 8, as shown in Fig. 1. With this arrangement of the shields 8^a 50 in the burner outlet 8, the shields unite with the

outlet walls 9 to form a series of transversely spaced vertically elongated nozzles discharging through the intertube spaces.

Inlets 10 and 11 are provided above and below the outlet 8 for secondary or combustion air. 5 Each air inlet 11 is shown to be of greater vertical cross sectional area and height than the inlet 10 thereabove.

Angle-irons 12 and 13 extend along the outside of the furnace wall and are connected to brackets 10 14 on the burner 5 by means of rods 15 that are provided with turn buckles 15^a.

A row of deflecting blocks 16 is provided along the furnace side of the tubes 2 opposite the outlet 8. These blocks 16 may be held in place 15 against the tubes 2 by means of U-bolts 17 which fit around the shields 8^a. The blocks 16 are provided with curved surfaces 18 to fit against the tubes and with countersunk openings 19 for nuts 20 on the ends of the U-bolts 17. The front sides of the blocks 16 or the sides toward the burner 5 are rounded, as indicated at 20, to divide each vertically elongated stream of incoming fuel and project it in two sheets, one inclined upwardly and the other downwardly, so that these sheets of fuel 25 will be struck by the air entering through the ports 10 and 11 substantially at right-angles.

Plates 21 and 22 are attached to the outlet 8 to define one side of each inlet 10 and 11. A damper 23, somewhat conventionally shown in Fig. 1 of the drawings, is pivoted at 24 to the bracket 25 above the plate 21 and a loose damper 26 is pivotally attached at 27 to a bell crank 28 pivoted at 29. The damper 26 in its full open position rests upon a supporting plate 26^a, against which the lower portion of the damper continuously contacts when the damper is turned by the bell crank 28. Rods 30 are provided for operating the dampers 23 and 26, so that the inlets 10 and 11 can be partially or entirely closed.

A casing 31 surrounds the burner and dampers and may be supplied with air under pressure in any convenient way. A port 32 for a lighter may extend through the casing 31 into proximity to the outlet 8 for lighting the fuel.

The burner extends laterally and converges in a vertical plane and flares horizontally toward the outlet 8, thus causing the incoming mixture of air and fuel to spread out horizontally in a thin sheet. The sheet is divided by the fuel nozzles formed in the outlet section 8 into a row of horizontally spaced vertically elongated fuel streams, each of which strikes a corresponding deflector block 16 and passes in two portions in such directions that the streams of air entering 55

through the inlets 10 and 11 are struck substantially at right-angles, thus intimately mixing the fuel and combustion air. In this way, practically the entire volume of the furnace can be 5 utilized very effectively for combustion.

A series of blocks 33 form a drip ledge positioned above the upper secondary air inlet 10, that is to say, over the secondary air-ports and fuel outlets. The blocks 33 are held in place 10 by being fastened to the cooling tubes 2 in the wall. The function of this drip ledge is to prevent clogging of the ports by liquid ash or slag which may flow down the wall from above the ports.

15 I claim:

1. In combination, a furnace having vertically disposed tubes along a wall thereof, a burner having a narrow exit opening extending across a plurality of said tubes, and a deflector in 20 front of said opening, said deflector being attached to said tubes.

2. In combination, a furnace having vertically disposed tubes along a wall thereof, a burner having an exit opening extending across a plurality of the wall tubes, a secondary air conduit also extending across a plurality of the wall tubes, and a deflector in front of the exit opening of said 25 burner, said deflector being attached to the wall tubes, and serving to direct the fuel into the 30 secondary air.

3. In combination, a furnace having vertically disposed tubes along a wall thereof, a burner having an exit opening extending across a plurality of wall tubes, means to cause streams of 35 air to enter said furnace along opposite sides of said burner in angular relation thereto, and means to cause fuel from said burner to divide into vertically diverging streams flowing at an angle to said air streams.

40 4. In combination, a furnace having vertically disposed cooling tubes in a wall thereof, a burner flaring in a horizontal plane toward its exit end extending across a plurality of the wall tubes and means for causing a single stream of fuel issuing 45 from said burner to divide and change its direction, said burner being mounted on and in thermal contact with said tubes.

5. In combination, a furnace having vertically disposed cooling tubes in a wall thereof, a burner flaring in a horizontal plane toward its exit end, a secondary air conduit having an opening adjacent the exit end of said burner, and means for causing a single stream of fuel issuing from said 55 burner to divide and change its direction, said burner and said secondary air conduit extending over a plurality of wall tubes, and said burner being mounted on and in thermal contact with the tubes.

6. In combination, a furnace having vertically 60 disposed cooling tubes along a wall thereof, a burner having an exit opening extending across a plurality of the wall tubes, a deflector mounted in line with and near the exit end of said burner in contact with and cooled by the wall tubes, and means to cause secondary combustion air to mix with material from said burner after it has struck said deflector.

7. In a furnace, a wall, vertically disposed cooling tubes in said wall, a horizontally elongated fuel nozzle extending across a plurality of said tubes, a secondary air-port adjacent said fuel nozzle substantially coextensive therewith, and a drip ledge block in said wall over said fuel nozzle 75 and said secondary air-port.

8. In a furnace, a wall, vertically disposed cooling tubes in said wall, a horizontally elongated fuel nozzle extending across a plurality of said tubes and a deflector block mounted on two adjacent tubes on the furnace side of said fuel 5 nozzle.

9. In combination, a pulverized fuel and air delivery pipe, a fuel burner nozzle arranged at an angle to said delivery pipe, a conduit section connecting said delivery pipe and nozzle and comprising a fuel distributing plate arranged at an angle to the axes of said delivery pipe and nozzle to receive the impact of the fuel from said delivery pipe and distribute the fuel therefrom throughout said nozzle, said nozzle having an 15 outer section progressively flaring in one direction and progressively tapering in a transverse direction from the discharge end of said connecting conduit section, and a nozzle discharge section flaring towards its discharge end in a 20 direction transverse to the direction of flare of said outer nozzle section.

10. In combination, a furnace wall having a fuel burner port formed therein, a fuel burner nozzle arranged to discharge fuel through said 25 burner port in a series of streams extending transversely of the direction of fuel discharge, means at the inner side of said furnace wall and immediately beyond the discharge end of said nozzle for dividing each fuel stream into a plurality of streams diverging in a plane transversely of the series of fuel streams, and means for discharging a stream of combustion air through 30 said burner port into each of said diverging fuel streams.

11. In combination, a furnace wall having a fuel burner port formed therein and spaced cooling tubes extending across said burner port, a fuel burner nozzle arranged to discharge a fuel stream through said burner port elongated transversely of the length of said cooling tubes, deflectors mounted on and extending across the spaces between said tubes and immediately beyond the discharge end of said nozzle for dividing the fuel stream passing through the intertube spaces into 45 a plurality of streams diverging in a plane transversely of the direction of elongation of the main fuel stream, and means for discharging streams of combustion air through each of said intertube spaces into said diverging fuel streams. 50

12. In a furnace, a substantially vertical wall having a fuel burner port formed therein, cooling tubes at the furnace side of said wall, a fuel burner arranged to discharge through said burner port, and blocks mounted on and in thermal contact with said tubes and arranged to form a drip ledge on the furnace side of said wall superadjacent said burner port to prevent obstruction of said burner port and fuel burner by solid deposits from above. 55

13. In combination with a furnace wall having a fuel burner port formed therein and a row of cooling fluid tubes uniformly spaced across said burner port to form transversely spaced discharge openings therebetween, a fluid fuel burner comprising a single fuel distribution conduit terminating in a series of transversely spaced nozzles adjacent said cooling tubes and each discharging through a corresponding discharge opening, a combustion air casing at the outer side of said 70 furnace wall and surrounding said burner port, and means for passing air from said casing through said discharge openings in streams impinging on the streams of fuel discharged from said nozzles adjacent said furnace wall. 75

14. In a burner for pulverized fuel, a single fuel distribution conduit terminating in a plurality of fuel nozzles spaced along a furnace wall, means forming a plurality of downwardly inclined air passages located above said nozzles and means forming a plurality of upwardly inclined air passages located below said nozzles whereby the air jets discharged therefrom are caused to impinge upon the fuel jets discharged from said nozzles, and means at the discharge end of said air passages for selectively controlling the velocity of air discharged from said upper and lower air passages without changing the initial point of impingement of said air streams on said fuel jets.

15. In combination, a furnace wall comprising a series of horizontally spaced cooling tubes, a fuel burner adapted to discharge through said wall and comprising a flared fuel conduit having its discharge end extending transversely across the outer side of a plurality of said wall tubes and terminating in a series of separate fuel nozzles, said nozzles being spaced apart and arranged to discharge fuel through separate intertube spaces at an oblique angle to said furnace wall, and means forming an air passage through each of said intertube spaces directed towards and adjacent to the discharge end of the corresponding fuel nozzle.

16. In combination, a vertically extending furnace wall having a series of horizontally spaced cooling tubes extending along its inner side, a pulverized fuel burner adapted to discharge through said wall and comprising a flared fuel conduit having its discharge end extending transversely across a plurality of said wall tubes and terminating in a series of separate vertically elongated fuel nozzles, said nozzles being horizontally spaced apart and arranged to discharge a mixture of pulverized fuel and primary air through separate intertube spaces, and means for directing a stream of secondary air through each of said intertube spaces at an angle towards and impinging on the corresponding fuel and primary air stream adjacent said furnace wall.

17. In combination, a vertically extending furnace wall having a series of horizontally spaced vertically arranged cooling tubes, a fuel burner adapted to discharge through said wall and comprising a fuel conduit having its discharge end extending transversely across a plurality of said wall tubes and constructed to discharge a plurality of fuel streams through separate intertube spaces at an oblique angle to said furnace wall, and means for directing a stream of air through each of said intertube spaces at an oblique angle to said furnace wall and in a direction to impinge upon the corresponding fuel stream.

18. In combination, a furnace wall having a series of horizontally spaced cooling tubes associated therewith, a fuel burner adapted to discharge through said wall and comprising a fuel conduit having its discharge end extending transversely across a plurality of said wall tubes and constructed to discharge a plurality of separate fuel streams through separate intertube spaces with some of said fuel streams directed at one oblique angle to said wall and other fuel streams at a substantially opposite oblique angle to said wall, and means for directing a stream of air through each of said intertube spaces at an oblique angle to said furnace wall and in a direction to impinge upon the corresponding fuel

stream closely adjacent its point of entry into the furnace.

19. In combination, a furnace wall including a series of transversely spaced wall tubes, a series of transversely spaced pulverized fuel nozzles adjacent said wall tubes and constructed to discharge a plurality of fuel streams through separate intertube spaces at an oblique angle to said furnace wall, and means for directing streams of combustion air through said intertube spaces at an oblique angle to said furnace wall and in a direction to impinge upon corresponding fuel streams adjacent said furnace wall.

20. In combination, a vertically extending furnace wall having a burner port formed therein and a series of transversely spaced wall tubes extending across said burner port, a combustion air casing at the outer side of said furnace wall and surrounding said burner port, a series of transversely spaced pulverized fuel nozzles adjacent said wall tubes and constructed to discharge a plurality of fuel streams through separate intertube spaces, and means for directing streams of combustion air from said casing through said intertube spaces at an oblique angle to said furnace wall and in a direction to impinge upon corresponding fuel streams adjacent said furnace wall.

21. In combination, a vertically extending furnace wall having a burner port formed therein and a series of transversely spaced wall tubes extending across said burner port, a combustion air casing at the outer side of said furnace wall and surrounding said burner port, a pulverized fuel conduit extending through said casing and having its discharge end extending transversely across the outer side of a plurality of said wall tubes, said conduit terminating in a series of transversely spaced fuel nozzles adjacent said wall tubes and constructed to discharge a plurality of fuel streams through separate intertube spaces, and means for directing streams of combustion air from said casing through said intertube spaces in a direction to impinge upon corresponding fuel streams adjacent said furnace wall.

22. In combination, a vertically extending furnace wall having a burner port formed therein and a series of transversely spaced wall tubes extending across said burner port, a combustion air casing at the outer side of said furnace wall and surrounding said burner port, a pulverized fuel conduit extending through said casing and having its discharge end extending transversely across the outer side of a plurality of said wall tubes, said conduit terminating in a series of transversely spaced fuel nozzles adjacent said wall tubes and constructed to discharge a plurality of fuel streams through separate intertube spaces at an oblique angle to said furnace wall, and means for directing streams of combustion air from said casing through said intertube spaces in a direction to impinge upon corresponding fuel streams adjacent said furnace wall.

23. In combination, a furnace having a vertically extending wall, a series of pulverized fuel nozzles constructed to discharge a plurality of fuel streams through said wall with some of said fuel streams entering the furnace at an upward inclination to said wall and other fuel streams at a downward inclination to said wall, means forming a plurality of downwardly inclined air passages located above said nozzles and arranged to direct streams of combustion air to impinge upon corresponding upwardly inclined

fuel streams, and means forming a plurality of upwardly inclined air passages located below said nozzles and arranged to direct streams of combustion air to impinge upon corresponding downwardly inclined fuel streams.

24. In a furnace, a wall, vertically disposed cooling tubes in said wall, a horizontally elongated

fuel nozzle extending across a plurality of said tubes and air-ports above and below said fuel nozzle, the air-port below said fuel nozzle being of greater area than that above said fuel nozzle.

RALPH M. HARDGROVE.
